UNITED STATES PATENT OFFICE.

ARTHUR O. HUBBARD, OF MINNEAPOLIS, MINNESOTA.

SILO.

1,030,404.

Specification of Letters Patent. Patented June 25, 1912.

Application filed November 4, 1910. Serial No. 590,702.

To all whom it may concern:

Be it known that I, ARTHUR O. HUBBARD, of Minneapolis, Hennepin county, Minnesota, have invented certain new and useful 5 Improvements in Silos, of which the following is a specification.

The object of my invention is to provide a silo construction which will permit the use of metal uprights or bars in connection 10 with the intermediate wooden panels, suitable provision being made for preventing contact of the metal with the contents of the silo.

A further object is to reduce to a minimum the vertical seams or joints in the silo through which the acids contained therein may pass into contact with the skeleton metallic inclosure.

A further object is to improve the construction of the silo at the sides of the door opening therein.

The invention consists generally in various constructions and combinations, all as hereinafter described and particularly 25 pointed out in the claims.

In the accompanying drawings forming part of this specification, Figure 1 is an elevation of the lower portion of a silo embodying my invention, Fig. 2 is a horizontal 30 sectional view of the same, Fig. 3 is a sectional view on the line $y-y$ of Fig. 2, Fig. 4 is a front view showing the door frame, Fig. 5 is a sectional view on the line $a-a$ of Fig. 4, Fig. 6 is a horizontal sectional 35 view showing the construction of the joint between the panels, Fig. 7 is a sectional view illustrating the manner of bracing and securing the opposite portions of the door frame, Figs. 8 and 9 illustrate slightly modified constructions.

In the drawing, 2 represents the vertical panels of a silo, each consisting of a series of narrow wooden strips placed edge to edge in substantially the manner shown in my 45 Patent No. 741,403, issued October 13, 1903. In my former patent I employ wooden uprights between the panels. With the growing scarcity of lumber, these uprights have added materially to the cost of the silo and 50 I therefore prefer to employ a metal upright 3 having an inner web 4, side webs 5 and an outer web 6. This outer web forms practically a continuation of the web 4, the webs 5 being disposed upon opposite sides of the 55 upright and being preferably inclined inwardly to a slight degree, as indicated in

Fig. 6, to conform to the curvature of the walls of the silo. The edges of the panels 2 have recesses 7 formed therein by rabbeting the ends of the strips and into these 60 recesses the web 4 fits snugly, the ends of the panels abutting against the webs 4 and 5 and forming a close joint therewith. The recesses 7 terminate at the bottom or toward the inner surfaces of the panels in a deeper 65 recess 8, into which a tongue 9 is inserted to lock the panels together and prevent them from slipping out of place in case of shrinkage of the wood. These locking tongues are inserted at suitable intervals during the 70 erection of the silo and, if found necessary, may extend from the top to the bottom to more thoroughly separate the metal uprights from the acids of the silo contents. The web 6 has notches 10 therein at intervals 75 to receive hoops 11 which extend around the silo and clamp the metal uprights and the panels securely together.

On each side of the door opening, metal rails 12 are arranged, composed of channel 80 bar, and preferably of galvanized material. These rails receive the edges of the panels on each side of the door opening and form a seat for the edges of the doors 13, as shown in Fig. 2. Bolts 14 have their ends projecting through counter sunk holes in the rails 12 and riveted therein, and sleeves 15, mounted on said rods, having their ends 85 contacting with said rails, hold them in parallel relation. Cross bars 16 are mounted on 90 the doors and locking devices 17 are arranged to contact with the outer faces of the rails to clamp the bars against the inner faces thereof. These bars 16 are arranged between the hoops and the sleeves 15 and 95 may be utilized, with the hoops and sleeves, in climbing up the sides of the silo.

In Fig. 8 I have illustrated a modified construction which consists in placing a tongue 9' in the joint between the ends of 100 the panels and arranging this tongue parallel with the web 4 instead of crosswise thereof, as shown in Fig. 6. In Fig. 9 the tongue is entirely omitted, the web 4 fitting into the recesses formed in the abutting 105 edges of the panels to correspond, substantially, to the one shown in Fig. 6.

The metal uprights may be made of suitable weight and the width of the webs may be varied, if preferred, to suit the different 110 sizes of silos. These metal uprights may vary in form to suit different conditions

and I do not wish, therefore, to be confined to the construction herein shown. Various other modifications may also be made in the details of construction without departing 5 from the spirit of my invention.

I have shown the panels in this silo composed of comparatively narrow wooden strips, but do not confine myself to this construction as suitable blocks, such as tile, may 10 be substituted in place of the wooden strips to form vertical panels, the ends of the blocks abutting against the side and inwardly extending flanges of the metal bars.

I claim as my invention:

15 1. A silo composed of upright panels having abutting vertical edges, upright metal bars having inner and outer vertical webs, said inner webs projecting into the joints between the edges of abutting panels but 20 extending only partially therethrough, the inner portions of said joints preventing contact of the acids in the silo with said bars, side webs extending laterally from said inner and outer webs and coöperating with 25 said inner webs to form seats for the outer portions of the abutting edges of said panels, said outer webs projecting outwardly beyond said side webs, and hoops seated on said outer webs.

30 2. A silo composed of upright panels hav-

ing abutting vertical edges, the outer portions of said vertical edges having rabbets formed therein, upright metal bars having inner webs seated in said rabbets, the inner portions of said vertical edges forming a 35 close, acid-tight joint between said webs and the interior of the silo, side webs extending laterally from said inner web and forming angles therewith to receive the outer portions of the vertical edges of said panels, 40 outer webs forming outward extensions of said inner webs and projecting beyond said side webs, and hoops inclosing the silo and seated on the edges of said outer webs.

3. A silo composed of upright panels 45 placed edge to edge, upright metal bars, star-shaped, substantially, in cross section, bridging the joints between said panels on the outside of the silo, one of the webs of each bar extending into the joint between 50 the panels and forming, with other webs, a seat for the edges of the panels, another web projecting outwardly and having notches therein, and hoops seated in said notches.

In witness whereof, I have hereunto set 55 my hand this 24th day of October 1910.

ARTHUR O. HUBBARD.
